PORTABLE CRANE

Hiram S. Weatherby, Atlanta, Ga.

Application December 30, 1952, Serial No. 328,597

3 Claims. (Cl. 212—144)

1

This invention relates to portable cranes, and more particularly to an improved crane structure mounted on a truck body and adapted to be transported thereby over a conventional highway.

A main object of the invention is to provide a novel and improved power crane of the portable type which is adapted to be folded to a relatively compact condition when it is desired to transport the crane, the boom of the crane being foldable to reduce the bulk of the crane, whereby the crane may be transported over conventional highways.

A further object of the invention is to provide an improved crane of the type having a foldable boom, the crane being simple in construction, being easy to manipulate, and being arranged so that the boom thereof may be folded or unfolded in a relatively short period of time and with a minimum amount of human labor.

Further objects and advantages of the invention will become apparent from the following description and claims, and from the accompanying drawings, wherein:

Figure 1 is a side elevational view of an improved portable crane constructed in accordance with the present invention, the boom of the crane being shown in folded position and the crane being arranged for transportation over a highway.

Figure 2 is a side elevational view of the crane of Figure 1, shown with the boom thereof in partly extended position.

Figure 3 is a side elevational view of the portable crane of Figure 1, shown with the boom in fully extended position preparatory for elevation of the boom to an operative position.

Figure 4 is a side elevational view of the power crane of Figures 1, 2 and 3, shown with the boom elevated to its working position.

Figure 5 is an enlarged fragmentary horizontal plan view of the hinged portion of the boom of the power crane of Figures 1 to 4, showing the jack rods and their associated sleeves.

Figure 6 is a cross sectional detail view taken on the line 6—6 of Figure 5.

Figure 7 is an enlarged cross sectional detail view taken on the line 7—7 of Figure 5.

Referring to the drawings, a mobile crane of the type contemplated by the present invention comprises a truck vehicle having a body section 10 and a prime mover engine (not shown) located under the hood 11, the vehicle being provided with the road wheels 12. The crane unit comprises a superstructure 13 rotatably mounted on a base 14 and housing a suitable power engine, cable drums and controls (not shown).

2

Designated at 15 is an inboard boom section constructed of suitable structural members, such as the longitudinal elements 16 and the diagonal brace elements 17, as shown in Figure 5. The inboard boom section 15 is pivoted to the superstructure 13 at 18 for rotation in a vertical plane.

Designated at 19 is an outboard boom section which is hingedly connected to the upper outer end of the inboard section 15, as shown at 20, the inboard section 15 being provided with the hinged lugs 21, 21 and the outboard section 19 being provided with the spaced pairs of hinged lugs 23, 23 receiving the hinged lugs 21 therebetween and hingedly connected thereto by respective hinge bolts 24, as shown in Figure 5. The opposite corner portions of the adjacent ends of the inboard and outboard boom sections are provided with interengageable, apertured lugs, shown at 25 and 26 which may be at times brought into registry and connected by suitable bolts, to secure the boom in its extended position, such as shown in Figures 3 and 4.

Designated at 27, 27, are respective sleeve members which are pivotally connected to the side elements 16 of the inboard boom section 15 for rotation on a common transverse axis. As shown in Figure 7, the sleeve member 27 may comprise main body portions formed with reduced shank elements 28 extending through and rotatably secured to the respective side members 16, as by suitable nuts 29. As shown in Figure 1, the sleeve members 27 are spaced a substantial distance from the hinge connections 20 although being located near said hinge connections.

Designated at 30, 30 are respective jack rods which are hinged at 31, 31 to the opposite side elements 32, 32 of the outboard boom section 19 at distances from the hinge connections 20 substantially equal to the distances of the sleeve members 27, 27 from said hinge connections. The jack rods 30, 30 extend slidably through the sleeve members 27, 27. The jack rods 30, 30 are preferably of tubular stock, and their lower ends, as shown in Figure 1, are respectively engaged by hooks 33 secured to the ends of respective cables 34 extending over pulleys 35 rotatably mounted on the upper side of the inboard boom section 15, as viewed in Figure 1. The cables 34 are connected to a drag line 36 which is secured to and wound on a drum 36 mounted on the superstructure 13 and provided with driving means, not shown, for independently winding the reel or drum 36.

The outboard section 19 is provided at its end 55 with the conventional pulley means for support-

3

ing the load hook 37, and is provided with the load line 38 for controlling the movement of load hook 37, said load line 38 being wound on and controlled by a drum or reel 39 mounted on the superstructure 13 and powered by conventional means in said superstructure. Designated at 40 is the main boom line for controlling the elevation of the boom, when said boom is in its extended position, said boom line being connected to a reel or drum 41 mounted on the superstructure 13 and powered by conventional driving means carried by said superstructure.

In order to extend the boom to the operative position thereof shown in Figures 3 and 4, the reel 36 is rotated by its power means to elevate the jack rods 30 from the positions thereof shown in Figure 1 to the positions thereof shown in Figure 2, wherein the outboard boom section 19 has been elevated to a substantially vertical position, the inboard boom section 15 being supported on the top of the hood 11. After the outboard boom section 19 has been raised to the position thereof shown in Figure 2, the main boom line 40 is employed to control the further clockwise movement of the outboard boom section 19, as viewed in Figure 2, allowing said outboard boom section to descend by gravity to the position thereof shown in Figure 3, wherein the outboard boom section 19 is aligned with the inboard boom section 15 and is substantially horizontal. The interengaging lug elements 25 and 26 are then secured by suitable bolts, as above explained, whereby the outboard boom section 19 is rigidly connected in alignment with the inboard boom section 15. The boom may then be elevated to the working position thereof shown in Figure 4 by means of the main boom line 40 and its driving reel 41.

To fold up the boom for transportation of the crane, the above procedure is reversed, namely, the boom is first lowered to its horizontal position, shown in Figure 3, and the bolts are removed from the interengaging lugs 25, 26. The outboard section 19 is then elevated to its vertical position, shown in Figure 2, by means of the main boom line 40, after which the outboard boom section 19 is allowed to descend to the position thereof shown in Figure 1 by gravity, the descent of the outboard boom section being controlled by the drag line 35, as by suitably braking the reel 36 as the jack rods 30, 30 move downwardly through the sleeves 27, 27 during the descent of the outboard boom section 19 to the final position thereof shown in Figure 1.

While a specific embodiment of an improved power crane having a foldable boom has been disclosed in the foregoing description, it will be understood that various modifications within the spirit of the invention may occur to those skilled

in the art. Therefore, it is intended that no limitations be placed on the invention except as defined by the scope of the appended claims.

What is claimed is:

- 5 1. In a power crane, a base, a superstructure mounted on said base, an inboard boom section pivoted to said superstructure, an outboard boom section hingedly connected to the outer end of said inboard section, means for at times securing the boom sections in aligned positions, a sleeve member pivotally secured to the intermediate portion of said inboard section, an elevating rod pivotally secured to the intermediate portion of said outboard section and extending slidably through said sleeve member, a cable movably supported on said inboard section, means on the cable lockingly engageable with the free end of the rod, and a winding reel on said superstructure, said cable being connected to said winding reel.
- 10 2. In a power crane, a base, a superstructure mounted on said base, an inboard boom section pivoted to said superstructure, an outboard boom section hingedly connected to the outer end of said inboard section, means for at times securing the boom sections in aligned positions, a boom elevating cable connecting the free end of the outboard section of the superstructure, a sleeve member pivotally secured to the intermediate portion of said inboard section, an elevating rod pivotally secured to the intermediate portion of said outboard section and extending slidably through said sleeve member, a cable movably supported on said inboard section, means on the last-named cable lockingly engageable with the free end of the rod, and a winding reel on said superstructure, said last-named cable being connected to said winding reel.
- 15 3. In a power crane, a base, a superstructure mounted on said base, an inboard boom section pivoted to said superstructure, an outboard boom section hingedly connected to the outer end of said inboard section, means for at times securing the boom sections in aligned positions, a first winding reel on the superstructure, a boom-elevating cable connecting said first winding reel to the free end of the outboard section, a sleeve member pivotally secured to the intermediate portion of said inboard section, an elevating rod pivotally secured to the intermediate portion of said outboard section and extending slidably through said sleeve member, a cable movably supported on said inboard section, means on the last-named cable lockingly engageable with the free end of the rod, and a second winding reel on said superstructure, said last-named cable being connected to said second winding reel.
